Attorney.

UNITED STATES PATENT OFFICE.

JOHN BRISBEN WALKER, OF NEW YORK, N. Y.

CONTAINER FOR BRICK.

1,331,544.

Specification of Letters Patent.

Patented Feb. 24, 1920.

Application filed April 5, 1917. Serial No. 159,885.

To all whom it may concern:

Be it known that I, JOHN B. WALKER, a citizen of the United States of America, and a resident of the city of New York, borough 5 and county of Richmond, and State of New York, have invented certain new and useful Improvements in Containers for Brick, of which the following is a specification.

The object of this invention is to provide 10 an inexpensive tool of simple construction for the economical, rapid and safe handling of brick, tile and similar material, and a saving absolutely of all destruction of brick by breakage. This is effected by providing 15 a container suitable for hand carrying. Loaded at the kiln, it simplifies the process of loading between the kiln, the car or boat. It permits the loading of brick on the car or boat with an expenditure of labor of 20 from twenty to forty per cent. less than that now required for transferring brick from wheelbarrow or kiln car to boat or car. It also saves from twenty to forty per cent. of the labor required for unloading from 25 boat or car to truck. If brick are hauled to storage yard, it again saves from twenty to forty per cent. of the labor required for unloading and reloading. At the building, brick are deposited without breakage, thus 30 saving the considerable percentage of brick broken in the present process of dumping. When brick are taken from the street to the wall, there is another considerable saving, and finally, instead of being dumped on the 35 floor and picked up by the worker, the container, placed on the wall itself, at the side of the mason, so that he takes each brick from the container by a lateral motion of his hand, serves the greatest economy of motion, covering the shortest possible distance, 40 and eliminates the back-breaking process of stooping for each additional brick.

A further object is to provide a container 45 which may be folded into a compact form for return and reuse, so that it will be economical to load the container at the kiln and permit the brick to remain undisturbed therein until withdrawn at the building wall.

50 A further object is to provide such a container with a bail or handle permanently attached thereto, but constructed in such manner as not to interfere with the folding up of the container for return shipment.

55 A further object is to provide such a container with walls of wire mesh so organized

that it will have points of increased thickness where the bricks will receive support, which points are most simply the crossing points of the mesh, and these will underlie 60 the area of the brick which they support and no brick will bear upon its support at any edge or corner and thereby render the corner liable to chipping.

A further object is to provide containers 65 of such construction that when loaded they may be stacked one above the other for storage or transportation, and when so stacked the bottoms of the upper containers will each rest upon the brick in the container 70 below with the points of bearing overlying the area of the brick and not at any edge or corner.

In the accompanying sheet of drawings 75 which forms a part of this application—

Figure 1 is a perspective of a container embodying my invention, the contents being indicated with dotted lines,

Fig. 2 is a plan view of the container folded for return shipment, and 80

Fig. 3 is an edge view of the same.

The container comprises a bottom section *a* and two end sections *b*, *b*. The sides of the containers are open, and the interior dimensions are such that the distance between the two open sides, which is the width of the bottom and the end sections, is slightly in excess of the length of a brick. The other horizontal interior dimension in the form shown is about three-quarters of an 85 inch in excess of the combined width of four brick and the depth is close to the combined thickness of six brick. This form consequently provides for holding twenty-four brick, but these multiples may be greater or 90 less, depending upon the density of the brick to be handled, and the load which is found most suitable to put upon the laborers employed. 95

There is a hinge connection between each 100 end section and the bottom section so that the end sections may be folded over onto the bottom section. The hinge is conveniently formed by eyes *c*, *c* at the lower ends of the vertical strands of the end sections which engage the end portions of a frame *d* which bounds the bottom section. The center line of the hinge is offset from the plane of one of the two sections hinged together in order that they may be folded into a parallel relation with one lying on the other. As shown 111 the offset is conveniently made with respect

to the plane of the side section, the eyes being offset for the purpose, as they may be of lighter gage wire which is more readily bent than the frame of the bottom section.

5 A bail or handle is provided which consists of a middle link *e* and two side links *f*, each consisting of a length of wire with eyes formed at the ends. The side links are connected to eyes *g*, *g* at the upper edges of the 10 end sections of the container, preferably through short links or rings *h*, *h* to increase the flexibility so that the bail will fold and permit the end sections to fold down on the bottom section. The links are of suitable 15 relative lengths to permit of this. The middle link in order to have sufficient stiffness is of heavier gage wire than the side links which are subjected only to tensile strains. A fiber handpiece *i* is hooked to the middle 20 link to afford a suitable handhold.

Within the frame of the bottom section are stretched longitudinal strands *j*, *j* and cross strands *k*, *k*, the number of the latter being double that of the brick in the bottom 25 layer so as to bring the crossing points with even spacing, which are the points of increased thickness to afford support within the area of the brick and not at any edge or corner and thereby render the corner liable 30 to chipping. This increased thickness at the crossing points also brings the points of support for the container when stacked within the area of the brick in the container 35 underneath, and permits the bail to be folded between without interfering with the bearing.

The bricks are loaded in the container at the kiln, and the container is conveniently used in all of the transfers up to the wall in 40 which the bricks are built. When the container is on the wall, by reason of the brick being in a single vertical bank and there being no sides to the container adjacent to the brick ends to interfere with the handhold the brick may be grasped and withdrawn with facility. And further, by reason of the brick being laid flat in the container, they do not have to be turned to

bring them into position for laying in the wall, and go from the container to their 50 places in the wall in substantially straight lines.

Because, by the use of these containers, not a brick is broken between the kiln and the wall, the mason does not lose time in 55 trying to fit broken brick into place, and the wall is strengthened by being laid up with all whole brick and joints regularly broken.

The usual steps in transferring brick 60 from kiln to wall involve eight handlings at each of which this container effects material economy. These handlings are: from kiln to barrow, from barrow to boat or car, from boat to truck, from truck to storage 65 yard, from storage yard to truck, from truck to ground and building, from ground to platform or floor of building, and from floor or platform to the wall.

Economy of transportation is also served 70 in the construction of the container, which is so devised that the three sections comprising the sides and bottom lie flat against each other, and packed in bundles for return to the kiln the containers occupy the 75 minimum of space, and their construction provides the minimum of weight consistent with strength.

What I claim as new, and desire to secure by Letters Patent of the United States, is— 80

A container for brick the walls of which comprise a wire mesh bottom section and two end sections, the sides of the container being open, the interior dimension between the end sections being slightly in excess of a 85 multiple of the width of a brick and the interior dimension between the open sides being slightly in excess of the length of a brick, and the points of intersection of the wire mesh of the bottom section being 90 located so as to underlie the area of the brick, substantially as described.

Signed at New York, N. Y., this fourth day of April, 1917.

JOHN BRISBEN WALKER.
